United States Patent Office

Des. 208,929
Patented Oct. 17, 1967

208,929

CLOCK OR SIMILAR ARTICLE

Carl N. Johnson, Stratford, and William V. Judson, Westport, Conn., assignors to General Electric Company, a corporation of New York

Filed June 1, 1966, Ser. No. 2,502

Term of patent 3½ years

(Cl. D42—7)

Fig. 1.

Fig. 2.

Fig. 3.

Fig. 4.

Fig. 5.

Fig. 6.FIG. 1 is a front perspective view of a clock embodying our new design;

FIG. 2 is a front elevational view thereof;

FIG. 3 is a top plan view thereof;

FIG. 4 is a bottom plan view thereof;

FIG. 5 is a side elevational view thereof; and

FIG. 6 is a rear elevational view thereof.

The markings on the ornamental face panels indicate a continuing pattern.

We claim:

The ornamental design for a clock or similar article, substantially as shown and described.
